[57] CLAIM

The ornamental design for a toy railroad car railer or similar article, substantially as shown and described.

DESCRIPTION

FIG. 1 is an isometric view of a toy railroad car railer or similar article showing my new design;

FIG. 2 is a top plan view;

FIG. 3 is an elevational view of one side, the opposite side being a mirror image thereof;

FIG. 4 is a bottom plan view;

FIG. 5 is an end elevational view, taken from the right of FIG. 2; and

FIG. 6 is an end elevational view thereof, taken from the left of FIG. 2.
